UNITED STATES PATENT OFFICE.

IRA H. SPENCER, OF HARTFORD, CONNECTICUT, ASSIGNOR TO THE SPENCER TURBINE CLEANER COMPANY, OF HARTFORD, CONNECTICUT, A CORPORATE BODY OF CONNECTICUT.

CLEANING-TOOL.

1,104,148.

Specification of Letters Patent.

Patented July 21, 1914.

Application filed April 25, 1907. Serial No. 370,168.

To all whom it may concern:

Be it known that I, IRA H. SPENCER, a citizen of the United States, and a resident of Hartford, in the county of Hartford and State of Connecticut, have invented a new and Improved Cleaning-Tool, of which the following is a specification.

My invention relates to the class of tools used in connection with cleaning apparatus in which a current of air is created for the purpose of removing and conveying dirt, and the object of my invention is to provide a tool which may be easily manipulated and which may be readily applied to surfaces variously disposed; and a further object of the invention is to provide a device that may be readily applied to surfaces more or less obstructed by furniture or like articles.

A form of device in the use of which these objects may be attained is illustrated in the accompanying drawings, in which—

Figure 1 is a view, looking from the rear, of a portion of a tool embodying my invention with parts broken away to show construction, the handle being removed. Fig. 2 is a view in central cross-section through the tool, including the handle the outer end of which is broken away. Fig. 3 is a view in cross-section through the lower end of the handle and the attaching sleeve. Fig. 4 is a side view of the attaching sleeve with part broken away. Figs. 5 and 6 are edge and side views of the securing ring. Fig. 7 is a perspective view, on reduced scale, of my improved tool.

In the accompanying drawings the numeral 10 denotes the body of the tool having a chamber 11. This tool is quite narrow when compared with its length and has on the bottom a flange 12 extending completely around the tool, all portions of the flange being located in the same plane so that all parts of the narrow edge of the tool may be placed upon a flat surface. A mouth or inlet 13 extends from the bottom of the tool into the chamber 11. In the preferred form of construction filling pieces 14, secured in any desired manner, extend lengthwise of the tool, the ends of the filling pieces being located in the offset portions 15. Sufficient space is left between the filling pieces to provide the mouth 13. A hub 16 projects from the rear end of the tool at the upper part thereof, a swell being made in the upper part of the tool to partially

form this hub. A groove 17 is formed on the inner surface of the hub for the reception of a fastening ring 18. This fastening ring is a split ring, as plainly shown in Figs. 5 and 6 of the drawings. An attaching sleeve 19 of a size to fit within the hub 16 has a groove 20. This groove 20 is of a depth at least equal to the thickness of the ring 18. The sleeve 19 fits closely within the hub 16 and the ring 18, in the attachment of the parts, is compressed into the groove, which as before stated is of sufficient depth to receive it. As soon as the groove 20 is located opposite the groove 17 the ring snaps into place, being located with a portion in each groove, the groove 17 being preferably of a depth less than the thickness of the ring. A slot 21 extends from the end of the sleeve 19 for the reception of a stud 22 on the lower section 23 of the handle of the tool. A clamping screw 24^a fitting upon the stud 22 secures the handle to the tool.

The handle is preferably composed of sections 23 and 24 detachably united. The inner end 25 of the section 23 is located at an angle, preferably one of 45 degrees, to the outer end thereof, and the inner end 26 of the section 24 which is attached to the outer end 30 of section 23 may if desired, and as shown herein, be located at an angle to the outer end 31 of said section, and the term "outer" as used herein with respect to the handle sections applies to that part of a section located farthest from the tool. While it is not absolutely essential that the angle above described between the inner and outer ends of section 23 shall be one of 45 degrees, yet this is preferred, as I deem the best results to flow therefrom. The end 26 is shown as being formed at an angle to the main part of section 24, but the construction may be modified to a greater or less extent. A nut 27 is secured to the section 23 of the handle, this nut having a lip 28 overlying a flange 29 on the section 24 of the handle. By this means the two sections of the handle are detachably engaged in a manner to permit adjustment of one of the parts upon the other.

It will be noted that the device constructed as above described with that end bearing the tool located at an angle to the part of the handle to which it is secured, (and by the term "handle" is meant herein

all of that part except the tool proper which is swiveled to the handle,) embodies a structure in which the tool may be located in different angular positions while being maintained flat upon the floor. By turning the handle axially with the tool having its edges placed flat upon a surface and so maintained, the angular position of the tool with respect to the handle may be readily 10 changed, the free swiveled connection of the tool to the bent portion of the handle allowing such operation. As the tool is caused to assume these different angular positions with respect to the handle by the movement 15 of the latter, it is clear that when the tool has been placed in any desired angular position it may be held in such position by retaining the handle against rotation on its axis. Thus, by simply rotating the handle 20 on its axis to the desired degree different angular positions of the tool with respect to the handle may be maintained to place such tool in any position, the tool being freely moved to such position and easily maintained therein. This is of especial advantage 25 in the cleaning of cushions, furniture, car-seats and the like, or in removing dust from walls and like places. This angular arrangement of the end of the handle and 30 the tool freely swiveled thereon enables the latter to be readily inserted underneath articles of furniture or stationary articles in public buildings, as theaters, school houses and the like, as the handle will readily accommodate itself to such position to 35 allow the tool to be inserted underneath such articles without tipping the edges of the tool from contact with the floor. In use, the nut 27 is screwed tightly against the 40 flange 29, the section 24 of the handle thus being insured against turning movement on the section 23. The tool may be thus freely placed at any desired angular position with respect to the handle to enable it 45 to pass between obstacles, under articles of

furniture, or along moldings arranged in different positions. In fact, it enables the tool to be brought into practically every conceivable place or position which will permit its entrance or passage, the handle being readily positioned to accommodate the position of the tool or vice versa. 50

What I claim as my invention and desire to secure by Letters Patent is:

1. A cleaning implement including a 55 handle having a main section and a tool supporting section attached thereto by a joint constructed to permit rotary adjustment of the sections one with respect to the other, means for securing the joint to prevent relative movement of the sections, the tool supporting end of the tool supporting section being bent at an angle to that part secured to the main section of the handle, and a long narrow cleaning tool swiveled to turn freely 60 upon the outer end of said tool supporting section on an axis passing laterally and horizontally across the tool, said handle having an opening extending therethrough and said tool having a slot communicating with the 65 opening in the handle.

2. A cleaning implement including a handle comprising a main section and a tool supporting section, said sections having a 70 passage lengthwise therethrough, a joint securing said sections together to permit rotative adjustment, means for locking the sections against rotative movement, the tool supporting section having its lower end bent at an angle to that part secured to the main 75 section of the handle, a sleeve removably secured to the tool supporting section, and a long narrow cleaning tool swivelly mounted on said sleeve and wholly supported thereby, the axis of rotation of said tool passing 80 laterally across it in a horizontal direction. 85

IRA H. SPENCER.
